UNITED STATES PATENT OFFICE.

FRANK L. TOUPAL, OF CHICAGO HEIGHTS, ILLINOIS.

ENVELOP.

1,163,381.

Specification of Letters Patent.

Patented Dec. 7, 1915.

Application filed May 20, 1915. Serial No. 29,294.

To all whom it may concern:

Be it known that I, FRANK L. TOUPAL, a citizen of the United States, and a resident of Chicago Heights, in the county of Cook and State of Illinois, have invented an Improvement in Envelops, of which the following is a specification.

This invention relates to envelops and more particularly to closures therefor.

10 One of the objects of the present invention is the provision of a novel form of flap closure for retaining the envelop sealed against accidental opening thereof, and which may be opened without mutilating 15 the same.

Another object is to provide an envelop of this character which is simple in construction, thus reducing the cost of manufacture to a minimum, and which is effective 20 in carrying out the purpose for which it is designed.

25 The inventive idea involved is capable of receiving a variety of mechanical expressions, one of which, for the purpose of illustrating the invention, is shown in the accompanying drawing, in which—

30 Figure 1 is a plan view of an envelop constructed in accordance with the invention, the closure therefor being shown in blank. Fig. 2 is a view similar to Fig. 1 showing the closure in closing position. Fig. 3 is a section on the line 3—3 of Fig. 2. Fig. 4 is a view similar to Fig. 2 showing the closure in 35 opened position. Fig. 5 is a transverse section on the line 5—5 of Fig. 4, and Fig. 6 is a view similar to Fig. 1 showing a slightly modified form of the invention.

40 Referring more particularly to the accompanying drawing, in which like reference characters indicate similar parts, it will be seen that the body portion of the envelop comprises the front section 10, overlapping side flaps 11 and 12 and the end flap 13 which is adapted to be bent over and secured 45 to the side flaps or sections 11 and 12 for closing one end of the body portion. The side section 11 is provided with a transversely extending slot 14 spaced from the longitudinal edges of said section while the flap 12 is provided with a slot 15, one end of 50 which communicates with the longitudinal edge of said flap and registers with the slot 14 to form an opening for receiving a tongue presently to be described.

The end of the body portion opposite the flap 13 is provided with a flap closure 16 which is preferably rounded upon its edge, as shown, and which terminates, at its central portion, in a locking tongue 17 which preferably extends longitudinally of the envelop and comprises lateral wings 18 formed upon the longitudinal edges of the tongue and adapted to be folded on the dotted lines 19 in overlapping relation to each other to form a tongue of treble thickness, as clearly 65 shown in Fig. 5, the wings 18 are cut as shown at 19' for a short distance on the fold lines 19 adjacent the junction of the tongue 17 with the flap 16 and adhesive is applied to the entire surface of the wings and tongue 70 with the exception of the narrow strip indicated by 20. After the wings are secured together, this strip 20, together with the adjacent face of the wing, forms a locking groove which extends transversely of the 75 envelop in parallel relation to the slots 14 and 15 so that when the tongue 17 is inserted into said slots the upper edges thereof will engage in the groove and abut the bottom thereof as shown in Fig. 3. This construction will effectively prevent accidental 80 disengagement of the locking tongue from the slots, and in order to open said envelop it is necessary to insert a pencil or other implement between the flap 16 and the side 85 flaps 11 and 12, and by exerting a slight pressure on the latter flaps, the upper edges of the slots 14 and 15 may be disengaged from the locking groove, thus permitting the withdrawal of the tongue 17 without mutilating 90 the envelop in any respect.

In Fig. 6, there is shown a slight modification in which the flap 16 is provided adjacent the inner end of the tongue 17 with a reinforcing tab 21 secured to the rear face of 95 said flap. The slots 14 and 15 in the side flaps also having a reinforcing element 22 surrounding the same.

I claim:

1. An envelop comprising a body portion 100 having one open end and a transverse slot, a closure for said open end having a longitudinally extending portion consisting of lateral wings folded in overlapping relation and having the major portion of their surfaces secured together whereby to form a tongue of a width equal to or less than the width of said slot, and having an inner free

extension for engagement with the edge of the body at one side of the slot nearest the said open end of the body.

2. An envelop comprising a body portion having one open end and a transverse slot, and a closure for said open end consisting of a longitudinally extending tongue having

a free extension upon its inner face and at its inner end, said tongue being of a width equal to or less than the width of the slot 10 through which it extends, said extension engaging the edge of the body along the side of said slot nearest the open end of the body.

FRANK L. TOUPAL.
